UNITED STATES PATENT OFFICE.

JOHN J. ROUND, OF WAKEFIELD, MASSACHUSETTS.

PERPETUAL CALENDAR.

1,425,137.

Specification of Letters Patent. Patented Aug. 8, 1922.

Application filed December 9, 1921. Serial No. 521,095.

To all whom it may concern:

Be it known that I, JOHN J. ROUND, a citizen of the United States, and resident of Wakefield, county of Middlesex, State of Massachusetts, have invented an Improvement in Perpetual Calendars, of which the following description, in connection with the accompanying drawing, is a specification, like characters on the drawing representing like parts.

This invention relates to improvements in perpetual calendars and the object thereof is to provide a perpetual calendar which may be applied to or incorporated in a pencil, fountain pen, or like device.

A further object of the invention is to provide a perpetual calendar comprising a set of three relatively rotatable co-axial cylinders, preferably tubular in form, bearing respectively the names of the months of the year arranged in a predetermined sequence, the days of the months of the year arranged in tabular form, and the names of the days of the week, and in so constructing such cylinders that when two of the cylinders are set in a predetermined adjustment the manipulation of the other cylinder will serve to present a correct calendar for any select month of any year, except leap year. The calendar is also so arranged that by a simple adjustment a proper calendar for each of the months of a leap year may also be displayed.

A further object of the invention is to provide a perpetual calendar of the character described in which one of the tables may be engraved or printed upon and formed a part of the barrel of a pencil or pen or like device.

More particularly the invention comprises a perpetual calendar for pencils and the like comprising three co-axial, relatively adjustable, cylinders bearing respectively a weekly table displaying the names or initials of the days of the week in a predetermined order, a daily table having numerals indicating the days of the month arranged consecutively in rows and columns, in one of which the numerals progressively increase by seven, and a monthly table displaying the names of the months of the year in a predetermined sequence, such that by establishing a fixed setting between the cylinder bearing the monthly table and one of the other table bearing cylinders for January of any year,

(except leap year), a correct calendar for any month of that year may be displayed by so adjusting the third table bearing cylinder that the column of the daily table bearing the numeral "one" is placed in alignment with the name of the initial day of the selected month.

These and other objects and features of the invention will more fully appear from the following description and the accompanying drawings and will be pointed out in the claims.

In the drawings:

Fig. 1 is a view in elevation of a preferred form of my invention as applied to a pencil or similar device;

Fig. 2 is a similar elevation with the outer table bearing cylinder removed;

Fig. 3 is a vertical longitudinal sectional view diametrically of the pencil barrel and the table bearing cylinders which are mounted thereupon;

Fig. 4 is a horizontal sectional view on line 4-4, Fig. 1;

Fig. 5 is a horizontal sectional view on line 5-5, Fig. 1;

Fig. 6 is a horizontal sectional view on line 6-6, Fig. 3;

Fig. 7 is a view showing a development of the inner cylinders, which preferably are of the same diameter;

Fig. 8 is an elevation of a modified form of the pencil illustrated in Figs. 1, 2 and 3, comprising a larger aperture for displaying the table showing the names of the months of the year;

Fig. 9 is an elevation of a preferred form of the invention in which the position of the cylinders, bearing the table having the names of the months and numerals corresponding to the days of the month, are reversed from the position shown in the preceding figures;

Fig. 10 is a detail vertical sectional view of the upper portion of the device illustrated in Fig. 9, showing a preferred means for limiting the extent of rotation of the outer cylinder of the pencil illustrated in Fig. 9;

Fig. 11 illustrates a development of the upper and lower cylinders of the device shown in Fig. 9 which bear respectively tables containing the days of the months and the names of the months;

Fig. 12 is an elevation of a simplified

form of perpetual calendar embodying the invention;

Fig. 13 shows a development of the cylinders set in a predetermined relation to present a correct calendar for a selected month of a particular year;

Fig. 14 is a detail sectional view showing the means for setting the cylinders; and,

Fig. 15 is a plan view of the intermediate cylinder alone.

The selected forms of a perpetual calendar embodying my invention are illustrated herein as applied to, or embodied in, the cylindrical barrel of a pencil, pen, or other device such as may be conveniently carried in the pocket of the user, but it will be understood that such embodiments of the invention and other modifications may be employed in other relations within the scope 20 of my invention as defined by the claims.

In the embodiments of the invention herein illustrated the cylinders bearing the various tables are coaxially arranged and adapted for rotative, relative adjustment, but it will be readily understood that the cylinders may be provided with tables suitably arranged to enable relatively longitudinal adjustment of one or more of the cylinders to display the correct calendar for each month of the year by such adjustment and manipulation as will be obvious to those skilled in the art. It will, therefore, be understood that the embodiments of the invention particularly disclosed herein are of an illustrative character and are not restrictive and that various modifications in form, arrangement and construction of parts may be made within the scope of the invention as defined by the claims.

One of the preferred constructions which is illustrated in Fig. 1 comprises a central cylinder or barrel 1 having mounted upon it two tables bearing cylinders 2 and 3, preferably of the same diameter and adapted to be rotatably adjusted relatively to each other and fixed in predetermined adjusted positions, and a third cylinder 4 preferably telescopically mounted upon the cylinders 2 and 3 and also rotatably adjustable relatively to said cylinders.

As illustrated in Figs. 1 to 7 inclusive, the cylinder 2 bears a daily table having numerals indicating the days of the months arranged consecutively in rows superimposed in columns in which the numerals progressively increase by seven, that is to say, the numerals in the rows are in consecutive order 1, 2, 3, etc., and the numerals in the vertical columns increase by seven 60 downwardly, as, 1, 8, 15, etc.

The cylinder 3 bears a monthly table displaying the names of the months of the year in a predetermined sequence such that a predetermined adjustment or setting may 65 be made between the names of the months

and the columns containing the days of the month in the monthly table that a third cylinder bearing the names of the days of the weeks may be so positioned by placing the name of the day of the week, which is the 70 initial day of the month, opposite the numeral "one" on the monthly table, that a correct calendar is displayed by said table and can be readily read by the user.

A table bearing the preferred sequence of 75 the months is illustrated in Fig. 7 and is as follows:—

APR 30	JULY 31	
SEPT 30	DEC 31	80
	JUNE 30	
	28	
FEB 29	MAR 31 NOV 30	
	AUG 31	
	MAY 31	85
JAN 31	OCT 31	
APR 30	JULY 31	
SEPT 30	DEC 31	
	JUNE 30	
	28	
FEB 29	MAR 31 NOV 30	90
	AUG 31	
	MAY 31	

In certain of the constructions shown this sequence is reversed, but the order is unchanged.

Means are provided for setting the cylinders 2 and 3 relatively to each other in a fixed relation so that these cylinders may remain set throughout any year, excepting 100 leap year, and may be adjusted for leap year by rotatably adjusting the cylinders one step.

A convenient means for thus permanently adjusting the cylinders 2 and 3 for the year 105 comprises a series of seven notches in one of the cylinders and a co-operating lug in the other adapted to enter such notch. As illustrated in Figs. 2 and 7 the table bearing cylinder 2 is provided with a series of 110 recesses 5 and the cylinder 3 with a projection 6 adapted to enter any of the recesses 5. The monthly bearing cylinder 3 is provided with letters corresponding to the days of the week arranged consecutively 115 in a predetermined order preferably opposite the ends of the lines bearing the names of the months.

In order to set the calendar for any year one of these cylinders is detached from the 120 other and rotated relatively thereto until the numeral "one" in the daily table stands beneath the letter indicating the day of the week upon which the year enters. For example, for the year 1921, the first day of 125 January was Saturday. The numeral "one," therefore, on the calendar cylinder 2 is placed beneath the letter "S" representing Saturday which is inscribed or printed upon the monthly cylinder. The cylinder 4 is 130

then telescopically placed upon the cylinders 2 and 3. The cylinder 4 is provided with a sight opening 6 of sufficient area to display seven columns and five rows so that a table 5 is presented displaying a column for each day in the week and rows for the successive weeks. The cylinder 4 is also provided with a longitudinally arranged aperture 7 which may, with the table arranged as shown, be 10 located centrally of the sight opening 6 through which a column showing months upon the monthly table is visible.

In this construction the prearranged sequence of the names of the months is such 15 that when the cylinders 2 and 3 are set as aforesaid the relative rotation of the cylinder 4 to a point where a selected month of the year is visible through the aperture 7 will 20 so locate the daily calendar in the sight opening that the columns thereon will appear directly under the days of the week which are inscribed upon the cylinder 4 intermediate of the sight opening 6 and the aperture 7 through which the names of the 25 months appear. Thus after having once set the calendar it is merely necessary in order to use the same that the outer cylinder 4 be rotated until the name of the month is 30 visible through the aperture 7 whereupon the correct calendar will appear in the sight opening.

Any suitable means may be provided for limiting the relative movement of the cylinders and for clamping the cylinders in place. 35 In the construction shown in Figs. 1 to 7 inclusive the monthly cylinder 2 is fixedly secured to, or if desired may be made integral with, the barrel 1, or if desired the numerals may be inscribed directly upon 40 the barrel. The barrel or cylinder 2 desirably is provided with a flange 8 to form an abutment for the lower end of the cylinder 2 and also desirably is provided with a lug 9 which extends into a recess 10 in 45 the lower portion of the cylinder 4, the recess 10 being of sufficient length only to permit a relative rotation equaling the width of seven of the columns on the daily table inscribed upon the cylinder 2.

50 The cylinders 2 and 3 are normally retained in interlocked position by a cap 11 fitting upon the barrel and having a flange 12 extending downwardly upon the outside of the upper end of the cylinder 4. A pin 13 in said flange engages a notch in the upper end of the cylinder 4 to prevent relative movement therebetween. An expandible plug 14 is inserted in the upper end of the barrel and is provided with a head 15 of 55 larger diameter than the barrel adapted to engage frictionally the cap 11 so that it will hold the outer cylinder 4 from rotation relatively to the cylinders 2 and 3 when once adjusted for a selected month. The 60 plug 14 may be made of rubber or formed

in any suitable expandible form, and the top 15 may be formed of rubber or metal or may present an ornamental device.

In the construction shown in Fig. 8 the same relative arrangement of table bearing 70 in predetermined sequence of the names of the months and the table bearing the numerals indicating the days of the month are similarly disposed, but are not connected together. The rotatable cylinder 4, which 75 bears the days of the week, is provided with a sight opening 16 of sufficient area to display all of the months of the year and is so arranged as to be secured in fixed adjustment or setting relatively to 80 the cylinder bearing the monthly table 3. This is accomplished by providing the upper end of the cylinder 3 with a series of seven notches 17 adapted to be engaged by a suitable lug 18 on the cap 19. 85

In setting this form of calendar for a year the cylinder 3 bearing the monthly table is turned until the name of the month is opposite the letter of the week which corresponds to the day of the week for the 90 first day of January. The cap is then pressed downwardly to lock the cylinders 3 and 4 in this adjustment. If then the cylinder 4 is rotated relatively to the cylinder 2 until the numeral "one" appears under the 95 day of the week on the cylinder 4 which corresponds to the first day of any month a correct calendar for that month will be presented in the sight apperture. In this device the monthly sequence is reversed. 100

The construction illustrated in Figs. 9, 10 and 11 is similar to that disclosed in Figs. 1 to 7 inclusive except that the position of the cylinders 2 and 3 are reversed, the cylinder 2 bearing the daily table 105 being placed above the cylinder 3 which bears the names of the months in a predetermined sequence. In this construction, therefore, the monthly table is fixedly secured to, or integral with, the barrel 1. A 110 further modification in this construction consists in forming the upper end of the cylinder 4 with an inturned flange 20 which overlies the upper end of the cylinder 2. The upper end of the cylinder 2 is provided 115 with a recess 21 of a length equal to the width of seven columns, and a lug 22, extending downwardly from the inturned flanged end 20 into the recess 21, serves to limit the relative rotation of the cylinder 4 to the 120 cylinders 2 and 3.

A simplified form of the invention is disclosed in Figs. 12, 13, 14 and 15, in which all of the cylinders are of the same diameter. While this construction is less convenient it 125 has the advantage of enabling larger columns to be employed and consequently enables the numerals and lettering to be made more prominent.

In this construction the barrel 1 has fixed 130

ly secured upon it, or formed integral therewith, a lower cylinder 23 bearing columns having the names of the months arranged in the same predetermined sequence as above described. This sequence is illustrated in Fig. 13 and upon examination will be found to be the same in order as that shown in Figs. 7 and 11, although in its development the cylinder is cut along a different line. Immediately above the cylinder 23 a weekly cylinder 24 is located and is adapted to be set relatively to the cylinder 23 by interlocking members such as a pin 25 extending upwardly from the upper edge of the cylinder 23 adapted to enter any one of seven recesses 26 spaced apart the width of the columns designating the months. The cylinder 24 is provided with a series of columns containing the names of the days 20 of the week, these columns being of the same width as the columns containing the names of the months. The third daily cylinder 27, bearing numerals in rows and columns as above described, is superimposed upon the cylinder 25 and is provided with a pin 28 adapted to interlock any one of the seven recesses 26 in the cylinder 24, as these recesses may extend entirely across the under wall of the cylinder 24 as illustrated in Figs. 14 and 15. The cylinders 23, 24 and 27 may be secured in the barrel 1 by an expanding plug 29 of the character above described.

In order to set this calendar for any year the plug is removed and the cylinders separated. The cylinder 24 is then rotated about the barrel 1 until the column thereon containing the name of the day of the week is opposite the column containing January on the table bearing cylinder 23. The cylinders 23 and 24 then stand adjusted for any year except leap year.

In order to adjust the calendar for any month the cylinder 27 is rotated about the barrel until the numeral "one" appears in the column containing the day of the week corresponding to that of the first day of the month. The cylinder 29 is then moved end-wise toward the cylinder 24 so that the pin 28 will interlock with the groove in the cylinder 24 which it is opposite, and the plug inserted. This calendar may then be used for the selected month.

When it is desired to adjust the calendar for another month the upper sleeve 27 is moved longitudinally of the barrel until the pin 28 is disengaged and is then rotated until the numeral "one" stands in the column containing the name of the day of the week which ushers in the selected month. The cylinder is then again forced downwardly into place where it is held by the pin 28 and the plug 29 replaced.

It will be seen from the above disclosure that the invention may be embodied in various different constructions and that the rela-

tive arrangement of the cylinders, the manner in which two or more of them may be secured together, is relatively unimportant except for convenience in setting, manipulation and reading, and that the invention 70 contemplates broadly any arrangement of superimposed or associated table bearing cylinders in which the items of the tables are arranged in such predetermined sequence that they may be so adjusted as to present 75 correct calendars for the months of any year, and in which two of the cylinders may be set in a permanent relation which will be effective throughout any year but leap 80 year, but which may be adjusted for leap 85 year from and after the end of February by adjusting the setting one column from or after the end of February.

Having thus described my invention, what I claim as new, and desire to secure by Letters Patent, is:

1. A perpetual calendar comprising three co-axial relatively adjustable cylinders bearing respectively a weekly table displaying the names of the days of the week in a predetermined order, a daily table having numerals indicating the days of the month arranged consecutively in rows and columns in one of which the numerals progressively increase by seven, and a monthly table displaying the names of the months of the year in a predetermined sequence, adjustable interengaging members respectively upon the monthly table bearing cylinder and one of the other table bearing cylinders such that by establishing for a series of months a fixed setting between the cylinder bearing the monthly table and said interengaged table bearing cylinder a correct calendar will be displayed by so adjusting the third table bearing cylinder that the numeral "one" is placed opposite the name of the day of the week corresponding to the name of the first day of the selected month.

2. A perpetual calendar comprising three co-axial relatively adjustable cylinders bearing respectively a weekly table displaying the names of the days of the week in usual order, a daily table having numerals indicating the days of the month arranged consecutively in rows superimposed in columns in which the numerals progressively increase by seven, and a monthly table displaying the names of the months of the year in a predetermined sequence and the number of days of the respective months adjacent to said monthly names, adjustable interengaging members respectively upon the monthly table bearing cylinder and one of the other table bearing cylinders such that by establishing a fixed setting between the cylinder bearing the monthly table and said interengaged table bearing cylinder for January of any year (except leap year) a correct calendar for any month of that year will be 130

displayed by so adjusting the third table bearing cylinder that the column of the daily table bearing the numeral "one" is placed in alinement with the name of the 5 day of the week corresponding to the name of the first day of the selected month.

3. A perpetual calendar comprising three co-axially arranged rotatably adjustable cylinders bearing respectively a weekly table 10 displaying the names of the days of the week in a predetermined order, a daily table having numerals indicating the days of the month arranged consecutively in rows superimposed in columns in which the numerals 15 progressively increase by seven, and a monthly table displaying the names of the months of the year in a predetermined sequence adjustable interengaging members respectively upon the monthly table bearing 20 cylinder and one of the other table bearing cylinders such that by establishing a fixed setting between the cylinder bearing the monthly table and said interengaged table bearing cylinder for January of any year, 25 (except leap year), a correct calendar for any month of that year will be displayed by so adjusting the third table bearing cylinder that the column of the daily table bearing the numeral "one" is placed in alinement 30 with the name of the selected month, and by rotatably resetting said interengaging members to advance the monthly table bearing cylinder one column on March first of leap 35 year, a correct calendar for that and the following months of the year will be displayed by so adjusting the third table bearing cylinder that the column of the daily table bearing the numeral "one" is placed in alinement with the name of the selected month.

4. A perpetual calendar comprising two co-axially arranged rotatable, adjustable cylinders of equal diameter displaying respectively a daily table having numerals indicating the days of the month arranged 40 consecutively in rows superimposed in columns in which the numerals progressively increase by seven, and a monthly table displaying the names of the months arranged in a predetermined sequence, and 45 also bearing the names of the days of the week in sequence, means for establishing a fixed setting between said cylinders, and a third cylinder displaying a weekly table, enclosing the cylinders bearing the daily and 50 monthly tables, rotatably adjustable relatively thereto, having a sight opening so arranged that when the monthly and daily tables are adjusted to position the numeral "one" in alignment with the name of the 55 day of the week on the monthly table which corresponds to that of the first of January 60 of any year (except leap year) the rotation

of the cylinder bearing the weekly table to a position to bring the name of the day of the week on which the selected month begins 65 into alignment with the column bearing the numeral "one" will display a correct calendar for the selected month in said sight opening.

5. A perpetual pencil calendar comprising a pencil barrel having thereon a cylindrical section presenting a monthly calendar bearing the names of the months arranged in a predetermined sequence, a cylinder rotatably adjustable on said barrel bearing 70 a monthly calendar having numerals indicating the days of the months arranged consecutively in rows superimposed in columns in which the numerals progressively increase by seven, means for establishing a 75 fixed setting between said cylinders for a series of months and a rotatable weekly table bearing cylinder, enclosing said cylinders, and having a sight opening to display a monthly table and a narrow aperture to display the name of a month, said pre-arrangement of the months and the position of said narrow aperture being such that when the name of any month is visible through said aperture the correct calendar for that month 80 will be displayed in said sight opening.

6. A perpetual calendar comprising a pencil barrel having thereon a cylindrical section presenting a monthly calendar bearing the names of the months arranged in a 85 predetermined sequence and also bearing a table indicating the days of the week, a cylinder rotatably adjustable on said barrel bearing a monthly calendar having numerals indicating the days of the month arranged 90 consecutively in rows superimposed in columns in which the numerals progressively increase by seven, means for maintaining a predetermined fixed setting between said cylinders, such that the numeral "one" of 95 the daily table shall be in alinement with the name of the day of the week on the cylinder bearing the monthly table which corresponds to that of the first day of January of a selected year and a rotatable 100 weekly table bearing cylinder, enclosing said cylinders, and having a sight opening to display the monthly table and a narrow aperture to display the name of a month, said pre-arrangement of months and the 105 position of said narrow aperture being such that when the name of the month is visible through said aperture a correct calendar for said month will be displayed 110 in said sight opening.

In testimony whereof, I have signed my name to this specification.

JOHN J. ROUND.
